RECIPROCATING PUMP

Ross J. Rumore, Birmingham, Ala.

Application December 12, 1940, Serial No. 369,888

1 Claim. (Cl. 103—175)

This invention relates to reciprocating pumps.

An object of this invention is to provide a reciprocating pump structure by means of which a more even pressure may be provided in the water supply line.

Another object of this invention is to provide in a reciprocating pump structure, an improved means for mounting the check valves so that these valves may be examined and taken out without the necessity of taking down the entire pump structure.

A further object of this invention is to provide in a pump of this kind, an improved sealing means for sealing the piston rod in the pumping chamber.

A still further object of this invention is to provide an improved sealing gland in the crank chamber so that this chamber may be filled with a lubricant for lubricating the drawhead connected with the crank.

To the foregoing objects and to others which may hereinafter appear, the invention consists of the novel construction, combination and arrangement of parts as will be more specifically referred to and illustrated in the accompanying drawings wherein are shown embodiments of the invention; but it is to be understood that changes, variations and modifications may be resorted to which fall within the scope of the invention as claimed.

In the drawings:

Figure 1 is a detail side elevation partly broken away and in section of a pump constructed according to an embodiment of this invention.

Figure 2 is a fragmentary longitudinal section taken through the pump.

Figure 3 is a transverse sectional view taken on the line 3—3 of Figure 1.

Figure 4 is a fragmentary sectional view taken on the line 4—4 of Figure 1.

Figure 5 is a top plan view of the lower valve unit member.

Figure 6 is a bottom plan of the unit shown in Figure 5.

Figure 7 is a sectional view taken on the line 7—7 of Figure 1.

Figure 8 is a fragmentary sectional view taken on the line 8—8 of Figure 3.

Figure 9 is a fragmentary sectional view taken on the line 9—9 of Figure 5.

Figure 10 is a fragmentary sectional view taken on the line 10—10 of Figure 2.

Figure 11 is a plan view of the intake valve supporting means.

Referring to the drawings, the numeral 15 designates generally a storage tank in which water or

other liquid is adapted to be stored and the numeral 16 designates generally a reciprocating pump structure which is mounted on a base member 17 secured to the tank or reservoir 15. The pump structure 16 is operated by means of a power member 18 in the form of an electric motor or the like.

The pump structure 16 includes a crank housing 19 which has formed integral therewith, a downwardly extending standard 20 which has secured to the lower end thereof a base plate 21. The base plate 21 is provided with an elongated slot 22 forwardly of the standard 20 and a fastening bolt 23 is adapted to engage through the slot 22 and to

be threaded into the base member 17. The base plate 21 is also provided with a rearwardly opening slot 24 through which a fastening member 25 in the form of a bolt is adapted to extend. The bolt 25 is also threaded into the base member 17.

10 The crank chamber 19 has a crank shaft 26 journalled therein and a driven pulley 27 is secured to the crank shaft 26 outwardly of the housing 19 and is adapted to be connected to the motor 18 by means of a belt 28 or the like. The belt 28 engages about a driving pulley 29 which is mounted on the shaft 30 of the motor 18.

15 The housing 19 at its rear end is provided with a threaded opening 31 in which a threaded plug 32 engages. The plug 32 is provided with a flange

20 33 which is adapted to limit the extension of the plug 32 in the opening 31. The opening 31 is provided in order that the crank shaft 26 and the parts associated therewith may be readily examined and in order that a suitable lubricant may be initially mounted within the chamber 19. The chamber 19 at one side thereof is provided with an annular plate 34 which is secured to the chamber 19 by fastening devices 35. The plate 34 is sufficiently large so that the crank 26 may be inserted in the chamber 19 upon removal of the plate 34.

25 The crank chamber 19 has mounted therein a drawhead cylinder 36 in which a drawhead or piston 37 is slidably mounted. The cylinder 36 is supported with the longitudinal axis thereof at

30 right angles to the longitudinal axis of the crank shaft 26 by means of a pair of supporting webs 38 which are formed integral with the side walls of the chamber 19 as shown in Figure 10. A connecting rod 39 is connected as at 40 to the offset 41 of the crank shaft 26 and the other or forward end of the connecting rod 39 is connected as at 42 to a wrist-pin which is mounted in the drawhead or piston 37.

35 A sealing gland generally designated as 43 is mounted in the forward wall 44 of the crank

chamber or housing 19 and a plunger rod 45 is slidable through the sealing member 43 and is threadably connected as at 46 to the drawhead or piston 37. The gland 43 comprises a threaded plug 47 which is threaded in an opening 48 formed in the forward wall 44 and the plug 47 is provided with an outer flange 49 between which and the forward side of the forward wall 44 a gasket 50 is adapted to be interposed. The plug 47 is provided in its inner end with a recess 51 within which a plunger rod guiding member 52 is adapted to be mounted. The plunger guiding member 52 is preferably pressed or otherwise firmly mounted in the recess 51 and may be of conventional construction so that when the plug 47 is tightly mounted in the opening 48, the guiding or sealing ring 52 will not only slidably guide the plunger rod 45 in the plug 47 but will also prevent any oil or other lubricant in the crank housing 19 from flowing forwardly through the axial opening 53 which is provided in the plug 47.

A pump housing generally designated as 54 is disposed forwardly of the crank housing 19 and is connected with the crank housing 19 by means of a connecting wall 55. The connecting wall 55 in its lower side is provided with an opening 56 so that when water or other liquid leaking out of the pump housing 54 or the crank housing 19 will drain out through the bottom of the connecting wall 55. An arcuate cap or plate 57 is removably secured by fastening devices 58 on a rearwardly projecting flange or ledge 59 which is formed integral with the rear wall 60 of the pump housing 54.

The pump housing 54 is supported in axial alignment with the crank housing 19 by means of a standard 61 which is formed integral with the pump housing 54 and a base plate 62 is formed integral with the standard 61 and engages the base plate 17. The plate 62 is provided with an elongated opening 63 forwardly of the standard 61 through which a fastening member 64 engages so that the base plate 62 may be adjusted lengthwise of the base member 17. The plate 62 is also provided with a rearwardly opening slot 65 which is in alignment with the opening 63 and also with the openings 22 and 24.

A fastening member 66 engages through the slot 65 and is threaded into the base member 17. The pump member 54 comprises a substantially cylindrical wall 67 which is formed integral with the standard 61 and with the rear wall 60. A forward wall or other head 68 is formed integral with the side wall 67 and a flanged plug 69 is threaded into an axial opening 70 which is formed in the head. The side wall 67 has formed therewith at one side thereof and at a point below the longitudinal center thereof, a substantially L-shaped intake member 71. The side wall 67 is provided with an opening 72 with which the intake member 71 communicates.

A pair of transversely extending partitions or inner walls 73 and 74 are formed integral with the side wall 67 and divide the side wall structure 67 into an intake chamber 75 and rear and forward outlet chambers 76 and 77. A cylinder 78 is mounted in the inner walls 73 and 74, the cylinder 78 being open at each end and extending slightly beyond the rear side of the rear wall or partition 73 and slightly beyond the forward side of the forward wall 74.

A plunger 79 is slidably mounted in the cylinder 78 and is connected to the forward end of the plunger rod 45. A sealing gland generally

designated as 80 is mounted in a threaded opening 81 formed in the rear wall 60 and provides a means for slidably sealing the plunger rod 45 in the rear wall 60.

The sealing gland 80 comprises a threaded plug 82 which is adapted to be threaded into the opening 81 and which is formed at its rear end with an annular flange 83. A gasket 84 is adapted to be interposed between the flange 83 and the rear side of the rear wall 60. A reduced threaded nipple 85 is carried by the rear end of the plug 82 and is provided with a bore 86 substantially larger in diameter than the diameter of the plunger rod 45. A sealing element 87 is adapted to be mounted partly in the bore 86 and partly at the rear end of the nipple 85 so that when a cap 88 which is threaded onto the nipple 85 is tightened, the sealing element 87 will be compressed about the plunger rod 45.

The plug 69 is provided with a central threaded opening 89 in which an air valve member 90 is mounted. The air valve member 90 is provided so that the desired air pressure may be placed in the pumping chambers 76 and 77. The pump housing member 67 is provided with a flat top wall 91 which is formed with a rear fluid opening or passage 92 and a forward fluid opening or passage 93. The rear passage or opening 92 is adapted to communicate with the rear chamber 76 and the forward opening 93 is adapted to communicate with the forward chamber 77.

The top wall 91 is also provided with a pair of spaced apart fluid passages 94 and 95 which communicate with the intake chamber 75. A valve cage member 96 is mounted in the opening 94 and a valve cage member 97 is mounted in the opening 95. An upwardly opening check valve member 98 is slidably mounted on a headed stud or bolt 99 which is threaded into the valve cage 96 and a spring 100 is mounted about the stud or bolt 99 and bears against the upper side of the valve member 98.

A valve member 101 engages the upper side of the valve cage 97 and is constantly urged into a closing position by means of a spring 102 which engages about a headed stud 103. The stud 103 is threaded into the central portion of the cage 97.

A substantially rectangular housing 104 is mounted on the top wall 91 and is provided with pairs of ears 105 which engage over ears 106 carried by the top wall 91. Fastening devices 107 engage through the ears 105 and are threaded into the ears 106. A gasket 108 is preferably interposed between the lower end of the valve housing member 104 and the top wall 91. The valve housing member 104 is provided with a top wall 109 which is formed with a pair of openings 110 and 111. A partition or dividing wall 112 extends between the openings 110 and 111 and divides the interior of the housing member 104 into a pair of fluid chambers 113 and 114. The partition 112 is preferably formed substantially S-shaped as shown in Figure 6 and when the housing member 104 is in applied position, the partition 112 is adapted to engage between the valve members 98 and 101 as shown in Figure 3.

The partition 112 provides a means whereby the intake openings 94 and 95 may be separated and whereby the opening 92 may be associated with the opening 95 and the opening 93 may be associated with the opening 94. A pair of valve cage members 115 and 116 are mounted in the openings 110 and 111, respectively, and spring-pressed valve members 117 and 118 are engage-

able with the upper ends of the valve cage members 115 and 116. The cages 115 and 116 are mounted in the top wall 109.

A dome or pressure member generally designated as 119 is mounted on top of the valve unit member 104 and comprises a dome-shaped body 120 which is provided at its lower end with a horizontal flange 121 and a vertical flange 122 extends downwardly from the horizontal flange 121.

The flange 121 is adapted to engage about the valve members 117 and 118 and fastening devices 122 are mounted in the valve unit member 104 and extend upwardly through the horizontal flange 121. Nuts 123 are threaded onto the bolts or fastening members 122 so that the dome or pressure member 119 may be readily removed from the valve unit 104 without loosening this unit 104 from the pump structure. The dome member 120 is at a point upwardly from the lower end thereof with a horizontally disposed wall 124 which is formed with an axial opening 125.

A valve cage 126 is threaded into the opening 125 and a downwardly closing spring-pressed valve 127 is engageable with the upper end of the valve cage 126. The valve cage 126 is inserted in the opening 125 from below the wall or partition 124. The dome 120 at its upper end is provided with a threaded plug 128 so as to either permit air to be discharged into the dome 120 or to permit the release of air. A laterally and downwardly extending outlet member 129 is formed integral with the dome member 120 and communicates with the dome 120 through an outlet opening 130 which is formed in the dome 120 above the valve member 127. The outlet opening 130 is positioned downwardly from the plug 128 so that when the pump is in operation, there will be a quantity of air disposed in the dome 120 above the outlet opening 130.

An outlet pipe 131 is threaded into the outlet member 129 and extends vertically and downwardly from the outlet member 129 and is connected by means of a coupling or a connecting member 132 with the tank 15.

A vacuum priming member generally designated as 133 is connected with the intake member 11 by means of a nipple or coupling 134. The coupling 134 is connected to the priming member 133 at the outlet side thereof and an intake pipe 135 is connected to the intake side of the priming member 133. The priming member 133 includes a lower liquid housing 136 and an upper dome 137 which has a priming plug 138 removably mounted therein. The drain plug 139 is mounted in the bottom of the liquid housing 136.

The motor 18 is preferably mounted on top of the crank case 19, being mounted on a horizontally disposed platform 140 which is formed integral with the top of the crank case 19. Fastening members 141 engage through the base 142 of the motor 18 and through the platform 140. A lubricant cup 143 is threaded into the crank case 19 so that the crank case 19 may be readily maintained in a filled condition with a suitable lubricant.

The dome 120 is preferably braced by means of a plurality of radially arranged and vertically disposed bracing webs 144 which are preferably cast integral with the dome 120 and with the flanges 121 and 122. In like manner the dome 137 is provided with a plurality of radially arranged and vertically disposed bracing webs 145.

In the use and operation of this pump struc-

ture, the motor 18 is adapted to be connected to a suitable source of electric current supply and upon operation of the motor 18, the pulley 27 will be rotated and the crank 26 will be rotated by the pulley 27. Rotation of the crank 26 will effect reciprocation of the drawhead 31 and the plunger rod 45. Reciprocation of the plunger rod 45 will reciprocate the plunger 79 in the cylinder 78. As the plunger 79 moves to the left as viewed in Figure 2, a suction will be created in the chamber 117 so as to effect a lifting of the intake valve member 98 thereby drawing water into the chamber 113. At the same time that the plunger 79 is moving to the left or in the direction of the intake chamber 116, the valve member 101 will be disposed in a closed position and the water or liquid in the chambers 116 and 114 will be forced upwardly so that the water in the chamber 114 will be forced past the valve 118. The movement of the liquid under pressure past the valve 118 will inset the valve 127 in the dome 120 and the liquid in the dome 120 will then flow outwardly through the outlet opening 130, through the outlet member 129 and downwardly through the pipe 131 into the tank 15. On the return movement of the plunger 79, wherein the plunger 79 moves to the right as viewed in Figure 2, the valve member 101 will be raised by the suction formed rearwardly of the plunger 79 and the valve member 98 will be maintained in a closed position by the spring 100 and the liquid in the chamber 113 will be forced upwardly past the valve member 117 and upwardly into the dome 120 past the valve 127.

By providing a pumping structure as hereinbefore described, it will be possible to readily examine the several check valve units forming part of the pumping structure without completely taking apart the entire pump. This is accomplished by first removing the dome structure 119 whereupon the dome valve 127 may be removed and examined. The removal of the dome 119 will also expose the valve members 116 and 117 so that if desired these valve members can be replaced. If it is desired to examine or replace the lower valve members 98 and 101, this may be accomplished by removing the valve unit member 104.

What I claim is:

50. In a reciprocatory pump having a housing for a reciprocatory plunger, said housing formed with a forward and rear outlet chamber, an intake chamber arranged between the outlet chambers, a pair of permanently open fluid passages on its top wall opening into said outlet chambers and an intake for said intake chamber; the combination of the top wall of said housing formed with a second pair of spaced aligned fluid passages opening into said intake chamber and arranged between and angularly related with respect to said first pair of passages, a pair of normally seated spring controlled valves for said second pair of passages, an open bottom valve housing detachably secured upon said top wall for said pair of valves having an upper end wall provided with a depending substantially S shaped partition dividing said valve housing into a pair of open bottom compartments, each compartment having a passage of each of said pairs of passages opening thereinto, said upper end wall of a valve housing being formed with a pair of spaced aligned passages having their axes offset with respect to the axes of said second pair of passages and each opening into a compartment, a second pair of normally seated spring

controlled valves for said passages in said upper end wall, said second pair of valves being substantially smaller than said first pair, a pressure housing having a delivery outlet and including an enlarged annular open bottom lower portion detachably secured upon said upper end wall, a dome-shaped upper housing portion of reduced diameter and of greater length than said lower portion, a horizontal partition in said upper portion between the horizontal median and lower end of the latter, said annular lower portion enclosing said second pair of valves, said

horizontal partition having an axially arranged fluid passage, a normally seated spring controlled valve for the passage in said partition, and a seat for said valve, said seat being constructed with a screw-throated barrel, and an outwardly extending flange on the lower edge thereof, said seat in said valve being adapted to be removed from the under side of said horizontal partition and said flange of said seat being adapted to contact the under seat of said partition.

ROSS J. RUMORE.
